UNITED STATES PATENT OFFICE.

TILLIE J. BROWNING, OF PHILADELPHIA, PENNSYLVANIA.

COLLAR-SUPPORTER.

1,111,359.

Specification of Letters Patent. Patented Sept. 22, 1914.

Application filed February 2, 1914. Serial No. 815,892.

To all whom it may concern:

Be it known that I, TILLIE J. BROWNING, a citizen of the United States, residing at Philadelphia, county of Philadelphia, and State of Pennsylvania, have invented a new and useful Improvement in Collar-Supporters, of which the following is a full, clear, and exact description, reference being had to the accompanying drawings, which form a part of this specification.

The object of my invention is to provide a collar supporter of that type comprising a frame member adapted to surround the neck and a plurality of upright arms projecting from the frame member at intervals.

The object of the invention is to provide a supporter of this type that will be practical to apply either to a stock collar that binds the neck closely or to the soft, high ruching loosely encircling the neck and terminating at any desired place on the front of the gown.

More specifically, the objects of the invention are to cheapen and facilitate the manufacture of the supporter and to enable it to be readily altered in size and shape either by way of increasing or diminishing the length of the frame member or by independently increasing or decreasing the height of any of the upright arms, thereby adapting the supporter to collars of varying size and shape.

In constructing my supporter I take a wire of indefinite length and corrugate or flute the same uniformly so that it presents a wave like appearance from end to end. At intervals this wire is bent at right angles to its main direction of extension and then back again. The two opposing sections of wire of which each form-maintaining arm is composed are so disposed that the inwardly extending rounded angles of the sections are on the same level, while at the junction of each arm and the base or frame member, the arm is twisted relatively to the frame member either once (that is, either half way around, or through an arc of 180 degrees) or is given a double twist (that is completely around or through an arc of 360 degrees), in order to make the connection between the frame member and arm rigid and permanent. The supporter may be sewed to the collar or ruffling at the extreme ends of the arms or at any one of the fluted sections of an arm. I provide special sewing members at the upper free ends of the arms, by form-

ing loops therein. The sewing loops at the upper end of an arm may be conveniently formed of two wave lengths of the wire or of a single wave length and may, if desired, be turned relatively to the remainder of the arm either half way around (a single twist) or completely around (a double twist) in order to close the loop. The abutting inward bends of two opposing waved or fluted sections afford a desirable location for the stitches in sewing, as it prevents the collar or lace from sliding down the supporting arms in case the end stitches stretch, or strain away from the end sewing member. I prefer to connect the two sections of the upright arm at the base of the loop and at their junction with the frame member by a double twist, as shown in the third upright arm from the left in Fig. 3, in order to make these connections as rigid and permanent as possible.

A supporter so constructed may be readily lengthened or shortened either in the frame member between adjacent arms or in the arms themselves; lengthening being effected by pulling out the wire to make the "waves" more shallow, and shortening being effected by compressing the wire in the general direction of its extension by deepening the "waves."

In order that my invention may be readily understood I have shown an embodiment of the same in the accompanying drawings, in which—

Figure 1 is a perspective view of a collar supporter embodying my invention. Fig. 2 is a portion of a wire blank from which the supporter is formed. Fig. 3 is a detail view of a portion of a collar supporter in which certain parts of the same are extended or contracted.

It will be observed that the frame member *a* and the arms *b*, *b*, etc., are made of a single piece of uniformly corrugated wire, that the two sections of which each arm is composed have their waves so arranged that the inwardly extending angles *w* of opposite sections are about on the same level and nearly touch each other, thus forming in each arm a series of approximately square spaces or diamonds *y* whose sides extend at an angle of forty five degrees, more or less, to the general direction of extension of the arm. This construction gives great rigidity to the arm and yet permits it to be readily lengthened or shortened.

In Fig. 3, I have shown several of the arms as of slightly different specific construction. The arms *b* and *c* are turned half way around relatively to the part of the wire forming the frame member *a*, while the arm *d* is turned completely around relatively to the part of the wire forming the frame member. The upper end of the arm *b* is formed of two wave lengths of wire, thus forming a double loop *m* providing a central depression to receive the sewing thread. The upper end of each of the arms *c* and *d* is formed of a single wave length of wire, thus forming a small loop for engagement with the thread. The loop *o* at the upper end of arm *d*, and the loop *p* at the upper end of arm *d'*, are turned relatively to the remainder of the arm to securely close the lower edge of the loop and impart to it greater permanence and rigidity. This, however, is not necessary, the loop *n* at the upper end of arm *c*, as well as the double loop *m* at the upper end of arm *b*, being unclosed except to the extent to which the opposing members of the arm approach actual contiguity.

To illustrate the capacity of the supporter for being altered in size, I have shown, in Fig. 3, a shortened section *i* and an extended section *j* of the frame member. I have shown, also, the vertical arm *b* of Fig. 3 shortened, and a vertical arm *d'* lengthened. With the proper kind of wire this may be readily and neatly accomplished by hand by an entirely unskilled person. Still another method of lengthening a vertical arm is shown in Fig. 3, in which the vertical arm *d* has two opposing "waves" pressed out flat, as shown at *r*, the remaining "waves" being unaltered. This means of extending the length of a member has the advantage of developing another style or form of collar support without marring its appearance or affecting the other desirable features specified.

The supporter is thus capable of being made of a single piece of wire of uniform contour throughout its entire length; and while of course, capable of being formed, in the first instance, into a supporter adapted to a collar of given shape and size, may be readily reshaped to adapt it to a collar of a widely different shape and size. It is thus

unnecessary for the user to select a supporter precisely adapted to a given collar, but a supporter approximating the size and shape desired may be selected and then may be easily reshaped to suit the collar.

Having now fully described my invention, what I claim and desire to protect by Letters Patent is:

1. A supporter for collars comprising a single neck-encircling frame member and upright arms, composed of a single length of wire of wave form throughout its length and extending successively circumferentially to form a section of the encircling base member, thence upward and downward to form an upright form-maintaining arm, thence circumferentially and upward and downward as before, and so on, the wave-lengths being short relatively to the length of each upright arm and circumferential section so as to provide a number of wave lengths contiguous one to the other in each arm and section, the two sections of each upright arm being twisted upon each other at the junction between the same and the integral neck-encircling member.

2. A supporter for collars comprising a single neck-encircling frame member and upright arms, the same composed of a single length of wire extending successively circumferentially to form a part of the encircling frame member, thence upward and downward to form two separate opposing sections constituting an upright form maintaining arm, thence circumferentially and upward and downward as before, and so on, the upward and downward sections being each of regular wave form and the wave lengths being short relatively to the length of the upright arms so as to provide a number of wave lengths in each of said sections, the two sections of an arm near their upper ends being twisted upon each other to form a terminal thread engaging loop.

In testimony of which invention, I have hereunto set my hand, at Philadelphia, on this 30th day of January, 1914.

TILLIE J. BROWNING.
